(57) **CLAIM**

We claim the ornamental design for the headstone border, substantially as shown and described.

DESCRIPTION

FIG. 1 is a front perspective view of our headstone border design;

FIG. 2 is a top plan view of headstone border of our headstone border design;

FIG. 3 is a bottom plan view of the headstone border of our headstone border design;

FIG. 4 is a front elevation view of the headstone border of our headstone border design;

FIG. 5 is a rear elevation view of the headstone border of our headstone border design;

FIG. 6 is a right side elevation view of the headstone border of our headstone border design; and,

FIG. 7 is a left elevation view of the headstone border of our headstone border design.
